UNITED STATES PATENT OFFICE.

JAMES HURST, OF SAN FRANCISCO, CALIFORNIA.

CARBURETOR.

Application filed February 27, 1923. Serial No. 621,630.

To all whom it may concern:

Be it known that I, JAMES HURST, a citizen of the United States, residing at San Francisco, in the county of San Francisco and State of California, have invented a new and useful Carburetor, of which the following is a specification.

This invention is a device for effecting the mixing of hydrocarbon and air, in the production of the usual explosive mixture required for the operation of internal combustion engines.

One of the objects of the invention is to provide a carburetor constructed to overcome the annoyances incident to the loss in buoyancy of the floats commonly employed to regulate the supply of hydrocarbon to the float chamber. A further object is to provide a float-like control member for the inlet valve of the float chamber of a carburetor, said member having approximately the same specific gravity as that of the fluid which it displaces, and a valve actuated thereby.

25 The invention will be hereinafter fully set forth and particularly pointed out in the claims.

In the accompanying drawing:—

Figures 1 and 2 are vertical sectional views illustrating two different types of well known carburetors now in general use, with the invention applied thereto.

Referring to Figure 1 of the drawing, 10 designates a carburetor casing, provided 35 with the usual mixing chamber 11, and a float chamber 12. Said float chamber communicates with the mixing chamber 11 through a nozzle 13, the outlet end of which is located within the usual Venturi tube 14. 40 The float chamber is also provided with the usual supply conduit 15. Pivotaly mounted within the float chamber is a lever 16, to one end of which is secured a valve 17, normally closing the inlet 15. To the other end of 45 the lever is secured a semi-buoyant actuator 18.

In practice, the actuator 18 is so constructed as to be as near as possible of the same density or specific gravity as that of the liquid in which it is to operate. In other words, it practically has no buoyancy with respect to said liquid. The closer the weight of the actuator to that of the liquid which it displaces, the greater the amount 50 of power or pressure that is available for opening the valve 17. Experiment has

demonstrated that an actuator made of oak wood will operate very satisfactorily in gasoline or the like, because its density is very close to the specific gravity of the gasoline, and it is the cheapest wood obtainable having this quality. The operation of the device is not impaired by the actuator becoming waterlogged. It is to be understood that the invention is not limited to an actuator constructed of oak wood, because the same may be constructed of various other materials and forms. For instance, it may be constructed in any of the various forms illustrated in my several co-pending applications for patent.

The valve 17 is illustrated as being hollow and abnormally large, and is filled with lead or other heavy material, having a substantially greater specific gravity than that of gasoline, the weight of the valve serving to maintain it on its seat when the actuator is submerged within the liquid contained within the float chamber.

In operation, assuming the float chamber 12 to be empty, the actuator will be depressed and the weight thereof will be sufficient to hold the valve 17 raised from its seat. As the liquid level rises within the chamber 12, the actuator 18 becomes submerged until it eventually exerts no influence upon the lever 16, thereby offering no resistance to the movement of the valve to its seat by the action of gravity. In other words, said lever is relieved of the weight of the actuator as the latter becomes wholly or partially submerged, and such complete or partial submergence allows the weight 19 to move the valve 17 to its seat. The weight of the valve is sufficient to resist the gravity pressure of the gasoline and to stop the flow thereof when the valve is seated, the seating of the valve being effected when the chamber is filled to the desired level. As soon as the liquid level starts to lower, the weight of the actuator 18 is exerted upon the lever 16, thereby acting to unseat the weighted valve 17. During the normal operations of the carburetor, the actuator will continue to function, to regulate the position of the valve 17, whereby gasoline is admitted or shut off, as the case may be, so as to maintain a normal working level within the chamber 12, the effect being the same as that obtained by use of the ordinary type of float.

In the form of carburetor illustrated in

Figure 2, the actuator 18^a is located within a float chamber 12^a, which is located within a casing separate and distinct from that containing the mixing chamber. The valve 5 17^a, provided with the weighted material 19^a, is actuated by means of levers 20, pivotally mounted within the float chamber, and positioned to engage notches 21 in the valve stem. Said levers are extended to 10 positions where they will be engaged by the actuator 18^a, as the latter moves downwardly under the action of gravity, when the liquid level is lowered.

In operation, as the liquid level rises 15 within the chamber 12^a, the actuator 18^a becomes wholly or partially submerged, whereby its weight is neutralized, whereupon the weight 19^a is free to force the valve 17^a to its seat. As the level lowers, 20 the weight of the actuator is applied to the levers 20, thereby raising the valve 17^a. The functioning of the device will be readily understood from what has already been stated in connection with the device illustrated in Figure 1.

The advantages of the invention will be readily apparent to those skilled in the art to which it appertains. It will be observed that a valve actuator of simple construction 30 is provided, which overcomes the annoyances incident to the loss of buoyancy of the floats now in common use, because the functioning of the present device is in no way dependent upon the ability of the actuator to float. Therefore its operation is in 35 no way impaired by becoming water-logged, thus insuring perfect operation under the usual carburetor conditions.

Having thus explained the nature of the 40 invention, and described an operative manner of constructing and using the same, although without attempting to set forth all of the forms of its use, or all of the forms in which it may be made, what is claimed 45 is:—

1. A carburetor of the character described comprising a casing provided with a float chamber having an inlet and an outlet, an inlet valve actuator movably mounted within 50 said chamber, said actuator being of approximately the same specific gravity as that of the fluid to be supplied to said chamber, whereby it will normally tend to submerge itself in the fluid in the said chamber, and an inlet valve for said chamber of sufficient weight to seat itself during submergence of said actuator.

2. A carburetor of the character described comprising a casing provided with a float 60 chamber having an inlet and an outlet, a lever pivotally mounted in said float chamber, an actuator of approximately the same specific gravity as that of the liquid to be supplied to said chamber, whereby it will normally tend to submerge itself in the fluid 65

entering said chamber, said actuator being secured to one end of said lever, and an inlet valve secured to the other end of said valve lever, said valve being of sufficient weight to seat itself during submergence of 70 said actuator.

3. A carburetor of the character described comprising a casing provided with a float chamber having an inlet and an outlet, an actuator movably mounted within said chamber, said actuator being of approximately the same specific gravity as that of the liquid to be supplied to said chamber, whereby it will normally tend to submerge itself in the fluid in the said chamber, and 75 an inlet valve controlled by said actuator, said inlet valve having sufficient weight applied thereto to cause it to seat itself during submergence of said actuator.

4. A carburetor of the character described comprising a casing provided with a float chamber having an inlet and an outlet, a lever pivotally mounted in said float chamber, an actuator of approximately the same specific gravity as that of the liquid to be 85 supplied to said chamber, whereby it will normally tend to submerge itself in the fluid entering said chamber said actuator being secured to one end of said lever, and an inlet valve secured to the other end of said 90 lever, said valve being of sufficient weight to seat itself during submergence of said actuator, the unsubmerged actuator being normally heavier than the weighted valve.

5. A carburetor of the character described comprising a casing provided with a float chamber having an inlet and an outlet, an actuator movably mounted within said chamber, said actuator being of approximately the same specific gravity as that of the liquid to be supplied to said chamber, whereby it will normally tend to submerge itself in the fluid entering said chamber, a hollow inlet valve controlled by said actuator, and a filling of weighting material 100 within the hollow portion of said valve, said material being sufficiently heavy to seat said valve during submergence of the actuator, the unsubmerged actuator being normally heavier than the weighted valve. 110

6. A carburetor of the character described comprising a casing provided with a float chamber having an inlet and an outlet, a lever pivotally mounted in said float chamber, an actuator of approximately the same specific gravity as that of the liquid to be supplied to said chamber, whereby it will normally tend to submerge itself in the fluid entering said chamber, said actuator being secured to one end of said lever, and an inlet valve secured to the other end of said lever, said valve having a hollow portion filled with a material to add weight thereto, said material being sufficiently heavy to seat said valve during submergence of said actuator, 125

the weighted valve being normally lighter in weight than the unsubmerged actuator.

7. A carburetor of the character described comprising a casing provided with a float chamber having an inlet and an outlet, a valve actuator of approximately the same specific gravity as that of the liquid to be supplied to said chamber, whereby it will normally tend to submerge itself in the fluid

entering said chamber and a weighted valve 10 normally weighing less than the actuator, said actuator and said valve being associated to move in unison said valve being of sufficient weight to seat itself during submergence of said actuator.

15

In testimony whereof I have hereunto set my hand.

JAMES HURST.
